UNITED STATES PATENT OFFICE.

HARRY N. EASTMAN, OF DAYTON, OHIO, ASSIGNOR OF ONE-HALF TO ERNEST A. EASTMAN, OF DAYTON, OHIO.

SPARK-PLUG.

1,205,441.

Specification of Letters Patent. Patented Nov. 21, 1916.

Application filed March 20, 1915. Serial No. 45,679.

To all whom it may concern:

Be it known that I, HARRY N. EASTMAN, citizen of the United States, residing at Dayton, in the county of Montgomery and 5 State of Ohio, have invented certain new and useful Improvements in Spark-Plugs, of which the following is a specification.

My invention relates to explosive engines and more particularly to ignition or spark 10 plugs therefor.

The object of the invention is to simplify the structure of such devices whereby they will not only be cheapened in construction, but will be more efficient in use, capable of 15 being easily and quickly disassembled and assembled, compression tight and unlikely to get out of repair.

A further object of the invention is to provide improved form of insulation which will 20 effectually prevent short circuiting in the event that the porcelain core is broken.

A further object of the invention is to provide an improved form of electrode whereby a broad fat spark will be induced.

25 With the above primary and other incidental objects in view, as will more fully appear in the specification, the invention consists of the features of construction, the parts and combinations thereof, and the 30 mode of operation, or their equivalents, as hereinafter described and set forth in the claims.

In the drawings, Figure 1 is a side elevation of the assembled spark plug forming the 35 subject matter hereof. Fig. 2 is a longitudinal sectional view of the same.

Like parts are indicated by similar characters of reference throughout the several views.

40 Referring to the drawings, 1 is the main bushing comprising a hexagonal head and a screw threaded extension 2 adapted to be engaged in the wall of the engine cylinder or in the ignition chamber thereof. The 45 main bushing 1 is counter bored to form therein a seat or shoulder 3.

Extending within the bushing 1 from the inner or screw threaded end thereof is a core 4 of porcelain, fire clay, glass, or other suitable material. This core 4 is provided with a conical truncated head 5 which projects peripherally beyond the main body of the core 4 forming a flange or seat 6 engaging upon the extremity of the screw threaded extension 2 of the main bushing 1. Interposed

between the seat or flange 6 of the core and the extremity of the bushing is a gasket or washer 7 preferably of copper or some other comparatively soft but heat resisting material which will conform to the opposing 60 faces of the bushing and core to form a compression tight joint.

Surrounding the main body of the core 4 and within the screw threaded extension 2 of the bushing is a sleeve 8 of fiber, gutta 65 percha, rubber or other insulating material. The seat or flange 6 of the head 5 of the core is preferably provided with a circular groove or depression 9 into which the lower end of the insulating sleeve 8 projects above the 70 level of the seat 3 within the bushing.

Surrounding the upper portion of the core 4 and projecting within the enlarged portion of the bore of the bushing is a second sleeve 10 of insulating material seated upon 75 the shoulder or offset 3 of the bushing. The first mentioned insulating sleeve 8 extends within the latter sleeve 10 and forms therewith a telescopic joint, as indicated at 11.

The core 4 is provided with a central bore 80 through which extends the primary electrode 12. This electrode is in the form of a bolt having at one end a head 13, the diameter of which corresponds with that of the apex of the conical head 5. Interposed between the head 13 and the apex of the conical head 5 of the core is a gasket or washer 14 of copper or other comparatively soft heat resisting material. The head 13 is 85 preferably circular and provided with parallel side walls. The shaft of the electrode extends through the bore of the core 4 and is screw threaded at its upper end to receive a compression disk 15 which bears upon the upper end of the insulating sleeve 10. By 90 tightening the compression disk 15 the several parts are firmly secured together. The insulating sleeve 10, bearing upon the shoulder or offset 3, forms an abutment for drawing the head 5 of the core tightly into 95 engagement with the lower end of the extension 2 of the bushing by the tightening of the compression disk 15 upon the shaft of the electrode. In order that the telescopic sleeves 8 and 10 may offer no resistance to 100 the tightening of the parts, a slight clearance or play is provided for in the telescopic or interlocking joint, as indicated at 16.

It has been found in practice that the rough usage to which spark plugs embody- 110

ing porcelain cores are subjected, particularly when used upon automobile motors, that the porcelain core is frequently cracked or broken by jar, heat, or concussion and that, in such case the ignition circuit is frequently short circuited by the arcing of the current through such crack or break in the porcelain. Such short circuit is very annoying to the driver because it is not a continuous short circuit but occurs only intermittently as the broken parts of the porcelain are jarred to and fro. The present construction is designed to overcome this difficulty by providing the insulating sleeve 5 and the sleeve 10 of non-breakable material around the porcelain core 4, the construction being such that these sleeves would afford sufficient insulation and protection to prevent arcing or short circuiting in the event that the porcelain core 4 is fractured or broken.

The usual binding screw 17, on the upper end of the electrode 12, serves as a lock nut to secure the parts in their adjusted position. Projecting from the inner edge of the screw threaded extension 2 is a second electrode or terminal finger 18 which extends first parallel with the axis of the spark plug, then angularly inward, and terminates in a portion extending parallel with the axis of the plug and spaced slightly away from but in the same plane with the head 13 of the primary electrode. This terminal portion of the finger or secondary electrode extends parallel with the face or periphery of the head 13, thereby affording an extended area across which the spark may arc. This construction affords a wide ribbon-like spark of great intensity. The head 13, being of comparatively large size, will remain comparatively clean and will not collect soot or carbon to interfere with the quality of the spark, as is the case when the spark is caused to jump from one point to another. The fact that the spark leaves the secondary electrode in a lateral direction and not from the end or terminal thereof, likewise reduces the difficulty due to clogging of the spark plug with soot, carbon, or other products of combustion.

From the above description it will be apparent that there is thus provided a device of the character described, possessing the particular features of advantage before enumerated as desirable but which obviously is susceptible of modification in its form, proportion, detail construction or arrangement of parts, without departing from the principle involved or sacrificing any of its advantages.

While in order to comply with the statute the invention has been described in language more or less specific as to certain structural features, it is to be understood that the invention is not limited to any spe-

cific details but that the means and construction herein described comprise but one mode of putting the invention into effect, and the invention is therefore claimed broadly in any of its possible forms or 70 modifications within the scope of the appended claims.

Having thus described my invention, I claim:

1. A spark plug comprising a bushing 75 having an internal shoulder or seat therein, a core, an electrode within the core, a separable sleeve of insulating material surrounding the core and engaging at one end the shoulder or seat within the bushing, a seat 80 for a second insulating sleeve formed in said first mentioned sleeve, and a second sleeve of insulating material also surrounding the core and seated within the first mentioned sleeve.

2. In a spark plug, a series of telescopic members each independently movable and each seated upon the other in adjusted position comprising a main bushing, a seat thereon, a sleeve of insulating material slidably mounted in said bushing and engaging said seat, a seat on said sleeve, a second sleeve of insulating material also slidably mounted in said bushing and engaging the seat upon the first mentioned sleeve, a core 95 slidably mounted within the said sleeves, a seat on said core engaging the last mentioned sleeve, and means for retaining said parts in adjusted positions.

3. A spark plug comprising a bushing 10 having an internal shoulder or seat therein, a core within the bushing having an external shoulder, a sleeve of insulating material surrounding the core and engaging at one end upon the shoulder within the bushing, 10 a second sleeve of insulating material surrounding the core and engaging the shoulder thereof, and abutting upon the first mentioned sleeve at its opposite end, and means for retaining the parts in adjusted 11 positions.

4. A spark plug comprising a bushing having an internal seat or shoulder, a core therein having a truncated conical head forming a shoulder upon the core, a sleeve 11 of insulating material surrounding the core and engaging the bushing shoulder, a second sleeve of insulating material surrounding the core and engaging the head and shoulder thereof, said second sleeve being 12 telescopically connected with the first sleeve, an electrode extending through the core, a head on said electrode registering with the apex of the truncated head of the core, and an adjusting member screw threaded upon 12 the electrode and engaging the first mentioned sleeve.

5. A spark plug comprising a bushing, a core within the bushing having a truncated conical head, said head having a concentric 13

groove therein, a sleeve of insulating material within the bushing and surrounding the core, said sleeve projecting into the concentric groove of the core head, and an electrode extending through the core.

6. A spark plug comprising a bushing, a core within the bushing having a truncated conical head, said head having a concentric groove therein, insulating material within the bushing and surrounding the core, one end of said material projecting into the

concentric groove of the core head and the other end thereof projecting above the bushing, making a continuous body of insulation, both ends extending beyond the 15 bushing.

In testimony whereof, I have hereunto set my hand this 15th day of March, A. D. 1915.

HARRY N. EASTMAN.
